(57) **CLAIM**

The ornamental design for a knife handle, as shown and described.

DESCRIPTION

FIG. 1 is a perspective view of the knife handle, showing my new design.

FIG. 2 is a left-side view thereof, the right-side being a mirror image.

FIG. 3 is a bottom view thereof.

FIG. 4 is a top view thereof.

FIG. 5 is a rear view thereof; and,

FIG. 6 is a front view thereof.

The broken lines shown in FIGS. 1 through 6 illustrate environmental structure that form no part of the claimed design.
